(57) CLAIM

The ornamental design for a therapeutic tourniquet wrap with pocket for cold/heat pack, as shown and described.

DESCRIPTION

FIG. 1 is a front elevational view of a therapeutic tourniquet wrap with pocket for cold/heat pack in a first position with arms of the therapeutic tourniquet wrap extended according to the present invention;

FIG. 2 is a top plan view of the therapeutic tourniquet wrap of FIG. 1, the bottom plan view being a mirror image of FIG. 2;

FIG. 3 is a rear elevational view of the therapeutic tourniquet wrap of FIG. 1;

FIG. 4 is a right side elevational view of the therapeutic tourniquet wrap of FIG. 1, the left side elevational view being a mirror image of FIG. 4;

FIG. 5 is a top plan view of the therapeutic tourniquet wrap of FIG. 1 in a second position with the arms of the therapeutic tourniquet wrap folded towards each other;

FIG. 6 is a cross sectional slice taken at 6-6 of FIG. 5;

FIG. 7 is a cross sectional view of the cross sectional slice taken at 6-6 of FIG. 5, shown in use with the cold/heat pack installed in the pocket;

FIG. 8 is a rear elevational view of the therapeutic tourniquet wrap of FIG. 1 in a third position with the arms of the therapeutic tourniquet wrap tied in a knot around inner loop of the therapeutic tourniquet wrap;

FIG. 9 is a rear view of the therapeutic tourniquet wrap of FIG. 1 in the third position, shown in use on a body part; and,

FIG. 10 is a top plan view of the therapeutic tourniquet wrap shown in use of FIG. 9.

The broken lines of FIG. 7 showing a cross section of the cold/heat pack and of FIGS. 9 and 10 showing portions of the body part are for environment illustrative purposes only and form no part of the claimed design. The graphical cross hatch pattern is a symbolic representation of a cloth material that exists uniformly across all surfaces on which it is shown.
